UNITED STATES PATENT OFFICE.

FRANCIS MURPHY, OF NEW YORK, N. Y., ASSIGNOR TO HIMSELF AND DAVID JONES, OF SAME PLACE.

FEED-PUMP FOR BOILERS.

SPECIFICATION forming part of Letters Patent No. 233,791, dated October 26, 1880.

Application filed March 20, 1880. (No model.)

To all whom it may concern:

Be it known that I, FRANCIS MURPHY, of the city, county, and State of New York, have invented a new and Improved Feed-Pump for 5 Boilers, of which the following is a specification.

The object of this invention is to provide an improved apparatus for forcing exhaust-steam from engine into boiler.

10 The invention consists of two vertical cylinders with pistons working within them, each one having two suction and two discharge openings, making four suctions and four discharges in all. The suction-pipes connect with 15 a closed tank, into which the engine exhausts, a check-valve preventing the passage of the exhaust-steam back to the engine. The upper discharge-pipes of these cylinders connect separately with the lower discharge-pipes, thus 20 making two pairs of pipes, which pairs have separate pipe-connections with a heater on the upper part of a steam-boiler, each separate pipe-connection being provided with a check-valve outside of said heater, thereby cutting 25 off all back-pressure between the heater and pump. The steam that drives the engine passes from the boiler to the engine through this heater, so that said steam is hot and dry, and thereby heats to the desired point the exhaust-steam that is forced into said heater by 30 the action of the pump. Hence it is that the exhaust-steam from an engine is returned again to operate the engine without condensing during its circulation from and back to said engine.

35 Figure 1 is a front elevation of the pump. Fig. 2 is a vertical sectional side elevation on line $x x$, Fig. 1.

Similar letters of reference indicate corresponding parts.

40 In the drawings, A represents the bed-plate of the pump; B, the standards, supporting on their tops the double-crank shaft C, on which are keyed the fly-wheels D D and driving-pulleys E E.

45 F F are the two upright pump-cylinders, secured side by side to the bed-plate A, each cylinder F F having an upper and lower valved supply-pipe, G G, on one side and an upper and lower discharge-pipe, H H, on the oppo-

site side, as shown, each pipe being provided with check-valves $a a b b$, respectively. Each cylinder F F is provided with a piston, I, whose rod I' passes up through a stuffing-box, J, in the cylinder-head and connects with a 55 pitman, K, whose upper end is secured on the crank-shaft C.

L L are guide-rods projecting upward from said cylinders F F, on which rods L L slide the cross-heads M M that embrace the piston-rods I' I'.

The pump herein described is run by belts from the engine passing over the driving-pulleys E E, the said cylinders F F operating alternately, or the said pistons I I alternating 65 with each other in their up-and-down strokes.

In operating this device it is designed that the engine shall exhaust into a closed tank, whence the exhaust-steam is prevented from returning to the engine by suitable valves. 70 The pump, having had suitable connections made with the steam-exhaust tank on one side and with the boiler-heater on the other side, and being put in motion, makes two strokes to one of the engine and draws from the steam-exhaust tank through the supply-pipe G G the exhaust-steam as fast as said steam is exhausted from said engine, so that said steam shall have little or no time to further condense 75 within said tank, and delivers said exhaust-steam through the discharge-pipes I I into the steam-heater, as hereinbefore set forth. The valves $a a b b$, respectively in the supply and discharge pipes G G I I, operate to prevent back-pressure from pump to exhaust-steam 80 tank and from heater to the pump-cylinders. Under these conditions this pump runs with very little expenditure of the engine's power, as the exhaust-steam enters the pump-cylinders 85 at nearly the pressure at which it escapes from the engine and operates with the full effect of this pressure in moving the pistons of the pump; hence the power given to the pump by the engine is only auxiliary, and the return of the exhaust-steam to the boiler at the high 90 temperature at which it may be returned by means of this device effects great economies in the fuel used to maintain steam in the boiler.

95 This pump may be used with great advantage in distilleries, oil-refineries, or other places 100

where much liquid is to be pumped, or where various kinds of liquids are to be pumped, for with properly packed pistons this pump can receive and deliver four kinds of liquids at a time without danger of one interfering with the other.

Having thus described my invention, I claim as new and desire to secure by Letters Patent—

- 10 The combination of the two cylinders F F, having pistons alternately operated from the same crank-shaft, and provided with upper

and lower valved supply-pipes G G on one side and on the other correspondingly-valved discharge-pipes H H, whereby different kinds of liquid may be independently pumped and the exhaust-steam taken from an engine and forced into a boiler without the intervention of water, as specified.

FRANCIS MURPHY.
